CLAIM

The ornamental design for a liquid dispensing gun and manifold, as shown and described.

DESCRIPTION

FIG. 1 is a perspective view of the liquid dispensing gun and manifold as a first embodiment of the invention;

FIG. 2 is a front elevational view taken of FIG. 1;

FIG. 3 is a left side view of the hot melt gun shown in FIG. 2;

FIG. 4 is a right side view taken of FIG. 2;

FIG. 5 is a top plan view taken of FIG. 2;

FIG. 6 is a bottom view taken of FIG. 2;

FIG. 7 is a rear view taken of FIG. 2;

FIG. 8 is a perspective view of a manifold as a second embodiment of the invention;

FIG. 9 is a front elevation view taken of FIG. 8;

FIG. 10 is a rear view taken of FIG. 9;

FIG. 11 is a left side view taken of FIG. 9 with the right side view being a mirror image thereof;

FIG. 12 is a top plan view taken of FIG. 9; and,

FIG. 13 is a bottom view taken of FIG. 9.

The elements shown in broken lines are for environmental purposes and relate to elements which do not form part of the claimed invention.
